SKATE

James Tracey, Boonton, N. J., assignor of one-half
to Jules H. Weinberg, Boonton, N. J.

Application July 6, 1933, Serial No. 679,236

5 Claims. (Cl. 208—173)

The object of this invention is to provide a 5
skate in which the frame is equally well adapted
to carry rollers or runners and which will be of
such construction that the skate may be readily
arranged to run upon two pairs of rollers or upon
one pair of rollers and a single roller. The inven- 10
tion also seeks to provide a skate which may be
quickly converted into the style desired and which
will firmly support the skater when in use. An-
other object of the invention is to provide a
mounting for the rollers which will permit the
rollers to rotate freely although they will be se- 15
curely held upon the frame. Other objects will
appear incidentally in the course of the follow-
ing description and the invention resides in cer-
tain novel features which will be particularly
defined in the appended claims.

In the annexed drawings, Fig. 1 is a side ele- 20
vation, partly broken away and in section, of a
roller skate embodying the present invention,

Fig. 2 is a bottom plan view of the same,

Fig. 3 is a transverse section on the line 3—3 of

Fig. 1,

Fig. 4 is a detail transverse section on the line 25
4—4 of Fig. 1,

Fig. 5 is a bottom plan view showing the skate
arranged to run upon a single roller at the front
and a pair of rollers at the rear,

Fig. 6 is a similar view showing the skate ar- 30
ranged with a single roller at the front and a
single roller at the rear,

Fig. 7 is a side elevation, partly broken away,
of the skate equipped with a runner for use upon
ice,

Fig. 8 is a transverse section on the line 8—8
of Fig. 7.

In carrying out the invention, there is pro- 40
vided a frame comprising a fore member or sole
support 1 and a heel member 2, the heel member
being formed with a heel stop 3 in the form of
an arcuate rim provided at the rear marginal edge
of the heel member and properly shaped to fit to 45
the heel of the skater's shoe. A strap 4 is thread-
ed through slots 5 provided in the heel member
adjacent the side edges thereof and provided
with a buckle 6 so that it may be passed around
the ankle of the skater and fastened to secure 50
the heel portion of the skate in place. The fore
member or sole support is provided on its under-
side, adjacent its front end, with a transverse
rib 7 which serves as a guide for the clamps 8
which secure the skate upon the sole portion of 55
the skater's shoe. These clamps, as best shown
in Fig. 4, comprise a base portion which is adapt-
ed to fit against the underside of the fore member

1 and an end member which rises past the edge
of the fore member 1 and has its extremity turned
inwardly, as shown at 9, whereby it will readily
engage around the edge of a shoe sole. The base
portion of the clamp is formed with an open-
ended longitudinal slot 10 adapted to engage the
respective end portion of the guide rib 7, as will
be understood, bolts 11 being fitted downwardly
through the sole support 1 and the ends of the
guide rib 7 and equipped with washers 12 and 10
nuts 13. The diameter of the washers 12 is greater
than the width of the slots or notches and,
consequently, they bridge the notches and bear
against the undersides of the clamps at the sides
of the notches so that when the nuts are turned 15
home the clamps will be firmly secured in a set
position. The sole and heel supports are con-
nected adjustably by a coupling bar 14 which has
its end portions disposed against the undersides
of the respective frame members, as will be under- 20
stood upon reference to Figs. 1 and 2, and pro-
vided with longitudinal slots 15, fastening bolts
17 being fitted downwardly through the respective
frame members and through the respective
slots and equipped with washers 18 and nuts 19 25
so that the coupling bar may be adjusted and
the frame members secured at any desired dis-
tance apart so that the skate may be made to fit
the foot of the skater. It should be noted that
the bolts 11 and 17 are all countersunk in the 30
respective frame members so that their heads
will be flush with the upper surfaces of the re-
spective members and, consequently, will not cut
into and unduly wear away the sole and heel of
the skater's shoe.

The frame members 1 and 2 which support the
sole and heel of the skater are provided on their
undersides with longitudinal flanges or bracing
plates 20 which are disposed at opposite sides of
the medial longitudinal line of the respective 40
members and spaced apart a distance equal to
or slightly greater than the width of the coupling
bar 14 so that said bar will be prevented from
rocking laterally upon either frame member but
will maintain the members in accurate longi- 45
tudinal alignment. The fore member 1 is pro-
vided at its extreme forward edge with a down-
wardly turned lip 21 which serves to connect the
front ends of the flanges 20 on said member and
thereby reinforces the front portion of the skate. 50
The lower edges of the flanges 20 are shaped to
provide downwardly extended portions, as clearly
shown in Figs. 1 and 7, the greatest depth of
the flanges on the fore member being located
between the ends thereof and the greatest depth 55

of the flanges on the heel member being located at the rear ends thereof. Alined openings are formed in the downwardly extended portions of the respective flanges to receive bolts or axles 22 and the skate rollers 23 are mounted upon these axles. As shown in Figs. 1, 2 and 3, which show the most generally adopted arrangement, a pair of rollers is provided upon each frame member and the rollers are disposed at the outer sides of the respective flanges 22, the axle 22 being long enough to extend beyond each flange a distance sufficient to support a roller. In this arrangement, a spacer 24 is fitted upon the axle between the flanges 20 so as to resist any tendency of the flanges to bend under use and the rollers are held upon the axle by nuts 25 and washers 26 fitted upon the ends of the axle, as clearly shown in Fig. 3. The skate rollers are provided with relatively large central openings and the circular walls of these openings are lined with rings 27 which form raceways for anti-friction balls 28 and cones 29 are fitted in the openings of the rollers to provide coacting raceways between which the balls are held. The cones 29 are fitted upon the ends of sleeves or hubs 30 which are fitted upon the ends of the axle at the outer sides of the respective flanges 20 and have their ends reduced so that they form seats for the cones 29 and maintain the properly spaced relation of the cones. The washers 26 and similar washers 31 which are disposed between the inner ends of the hubs and the flanges 20 are of such diameter that they extend beyond the circumferences of the hubs and bear against the outer sides of the cones, as clearly shown in Fig. 3, so that when the nuts 25 are turned home, the bearings will be firmly secured in place but no clamping pressure will be applied to the sides of the roller which are, consequently, free to rotate easily.

To further strengthen the structure and resist any tendency of the flanges 20 to spread, I provide bolts 32 which are inserted through the rear ends of the front flanges and the front ends of the rear flanges, as clearly shown in the drawings, and equipped at their ends with suitable securing nuts 33, a spacer 34 being fitted upon each bolt between the flanges so that the flanges will be braced and all tendency of the same to spread will be effectually resisted. It is also to be noted that the spacers 34 will rest against the underside of the coupling bar 14 and will thereby furnish additional supports for said bar and relieve the strain upon the securing bolts 17. When it is desired to have the skate run upon a single roller disposed between the flanges instead of pairs of rollers in which the rollers are disposed at the outer sides of the flanges, short axles 35 are substituted for the longer axles 22 and the hub members 30 are fitted in the rollers 23 in just the same manner as in the previously described arrangement, clamping nuts 36 being fitted upon the ends of the axle and turned home against washers disposed against the sides of the flanges to maintain the axle in place and support the roller. Upon reference to Figs. 5 and 6, it will be noted that the same frame may be used whether the skate is to run upon two pairs of rollers or upon two single rollers or upon 70 a pair of rollers and a single roller.

If it be desired to employ the skate upon ice, a runner or blade 37 is substituted for the rollers and the bolts 35 which are employed as the axles for single rollers are inserted through 75 the openings in the flanges and through open-

ings provided therefor in the runner so that the runner will be disposed and held midway the flanges 20. Fillers 38 are disposed between the flanges and the skate runner or blade, as clearly shown in Fig. 8, so that the blade will be held positively in the longitudinal medial line of the frame and will be thoroughly braced against warping. The fillers may be of any suitable material and will be shaped to conform to the outlines of the flanges and of such size that they will completely fill the spaces between the runners and the respective flanges. The runner or blade will also be preferably formed with a cut away portion 39 in its upper front corner adapted to abut the downturned lip 21 of the fore member of the frame so that the openings in the runner will be properly alined with the openings in the flanges and the fillers when the front end of the runner has been made to engage the lip.

From the foregoing description, taken in connection with the accompanying drawings, it will be seen that I have provided a very simple structure which may be employed either as a roller skate or an ice skate and may be converted from one form to the other very quickly and easily. The ground-engaging element, whether it be a runner or a roller, will be securely held in position so that it is not apt to become detached, and throw the skater. It will be understood, of course, that the flanges 20 are provided with openings, shown at 40 in Fig. 7, to accommodate the clamps 8 and the guide rib 7 reinforces the sole-supporting plate so that the skate frame will have ample strength to resist the strain placed upon it.

Having thus described the invention, I claim:

1. A skate comprising sole and heel-supporting members, parallel longitudinal flanges on the undersides of said members, a coupling bar having its ends fitted between the flanges on the respective members and adjustably secured to said members, ground-engaging elements carried by the flanges, spacers disposed between the rear ends of the flanges on the sole-supporting member and the front ends of the flanges on the heel-supporting member, and means for clamping the flanges against the ends of said spacers.

2. A skate comprising sole and heel-supporting members, a coupling bar connecting said members, longitudinal parallel flanges on the undersides of said members spaced from both sides thereof, the front ends of the flanges on the sole-supporting member being united by a downturned lip carried by the member, and means whereby a ground-engaging element may be mounted upon the flanges.

3. A skate comprising a supporting member, a transverse guide rib on the under face of said supporting member, clamps at opposite sides of said supporting member having base portions extending transversely of the supporting member against the under face thereof and formed with longitudinally extending slots open at their inner ends and slidably receiving the guide rib, and means at ends of said guide rib for securing the clamps in set positions.

4. A skate comprising a supporting member, a transverse guide rib on the under face of said supporting member, clamps at opposite sides of said supporting member having base portions extending transversely of the supporting member against the under face thereof and formed with longitudinally extending slots open at their inner ends and slidably receiving the guide rib, bolts extending downwardly through the sup- 75

porting member and end portions of the guide rib, washers fitted upon lower end portions of said bolts against the under face of the guide rib and having portions projecting from sides of the rib and bearing against the under faces of the base portions of the clamps, and securing nuts carried by said bolts and engaging the washers to force the washers into frictional gripping engagement with the base portions of the clamps to secure the clamps in set positions when the nuts are tightened.

5. A skate comprising a supporting member, flanges extending longitudinally of said member and depending therefrom in spaced relation to each other transversely thereof, a transverse guide rib on the under side of said supporting member extending through and beyond the flange, clamps having base portions fitting against the under side of the supporting member and formed with slots open at inner ends of the clamps and slidably receiving the guide rib with portions of the base portions of the clamps extending through the flanges and supported thereby, and means at ends of the guide ribs for securing the clamps in set position.
